UNITED STATES PATENT OFFICE

HILARY MILLAN, JR., OF NEW YORK, N. Y.

COMMERCIAL ENVELOPE

Application filed February 18, 1931. Serial No. 516,575.

This invention relates to new and useful improvements in an advertising envelope.

The invention has for an object the construction of an advertising envelope which is characterized by a division line extending from the top to the bottom on its front face and dividing the front face into two sections namely a left hand section for being printed with advertising matter and a right hand section for the name, address and other information ordinarily placed upon the face of an envelope.

As a still further object of this invention it is proposed to arrange a trademark at the central bottom of the advertising section or at the central bottom of the envelope.

A still further object of this invention is to construct an envelope which will help in all manners, the commercial relations and ways of announcing merchandise or commercial products all over the world.

A still further object of this invention is the construction of a device of the class mentioned which will help in such ways the commercial advertising at the very best and effective way, and in the mean time to provide the country with an unusual way of public service under the commercial lines.

It is proposed that the envelope according to this invention be used as regular envelopes in commercial service. The left hand section should be dedicated only with the idea of printing the products that may be announced by using the trademarks reserved by the commercial houses. A still further object of this invention is to construct the envelope so that in the lower part and between the two divided sections there should be the trademark "commercial envelope" fully printed or in any other manner scribed thereon.

A further purpose of this invention is the arrangement of perforations upon the face of the envelope in a manner which will facilitate tearing off the advertising section of the envelope so that it may be kept as a souvenir.

A still further object of this invention is to arrange perforations around a picture or other printed matter upon the advertising side of the envelope, to gum the back of the picture so that when a letter is placed with-

in the envelope the gum portion may be wetted to cause the picture to adhere upon the letter so that upon removal of the picture will be automatically torn out from the envelope.

And a still further object of this invention is the construction of an envelope of the class mentioned which is of simple durable construction, dependable in use and efficient in action, and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevational view of an envelope constructed according to this invention.

Fig. 2 is a view similar to Fig. 1 but illustrating a modified arrangement.

Fig. 3 is a fragmentary view similar to the lower central portion of Fig. 3, but illustrating a still further modified arrangement.

Fig. 4 is a fragmentary view similar to a portion of Fig. 2, but illustrating a still further modified arrangement.

Fig. 5 is a sectional view taken on the line 5-5 of Fig. 4.

The advertising envelope according to this invention comprises sheet material in the form of an envelope 10 and having a front face 11 divided by a line 12 which extends from the top to the bottom, thus forming two sections indicated by reference numerals 13 and 14 respectively.

The left hand section 13 is for the purpose of printing or in any other manner displaying the trademark or advertising matter of any form which subscribes to this invention. Reference numeral 15 indicates a printed advertisement on the section 13. The section 14 is for the purpose of printing the sender's address 16 and the name and address 17 of the receiver. A postage stamp 18 or other government mark, constituting the payment

for delivering the envelope, may be placed in the conventional position at the upper right hand corner of the envelope.

The envelope 10 may be of any size, made from any material, according to any design. As shown in Fig. 1, it is provided with a rear flap 19 allowing for the closing of the envelope after the insertion of the paper or papers. At the bottom of the section 13, the trademark "commercial envelope" indicated by reference numeral 19' is printed as shown on the drawing. In Fig. 2 the identical envelope illustrated in Fig. 1 is disclosed, which may be recognized by the corresponding numerals with the exception of the location of the trademark "commercial envelope". In this case this trademark is located at the bottom and central portion of the front face of the envelope.

In Fig. 3 another modified form of the invention has been disclosed, in which a line of perforations 20 serve to divide the envelope into two sections. In addition, the trademark 19' is blocked off by a top and bottom line 21 of perforations. At the sides substantially U-shaped cuts 22 arranged upon one side connect with the perforations 21 so that one may tear the lower portion of the envelope off for allowing insertion of one's finger within the opening thus created to tear the perforations 20. This allows the dismembering of the advertising section 13 of the envelope.

In Figs. 4 and 5 another modified construction of the invention has been disclosed, in which the advertising picture 15 or the like is surrounded by perforations 33. In addition, gum material 24 is on the rear of the picture or other advertising matter 15 within the boundaries of the perforations 23. In use, the gum 24 is first wetted and then the letter and other matter inserted in the envelope and the flap of the envelope sealed as is customary. When the envelope is opened and the letter removed, the advertising picture 15 will automatically be torn out from the front face of the envelope and in this manner attract attention to the advertisement.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. An advertising envelope, comprising sheet material in the form of an envelope having a front face divided by a perforated line extending from the top to the bottom so as to form a right hand and left hand section, miscellaneous matter or the like print-

ed upon the left hand section and the right hand section being for the purpose of the sender's name and address, the receiver's name and address, and the necessary postage stamp, a pair of spaced parallel transverse perforated lines at the base of said perforated line, and said sheet material being formed with cuts connecting the ends of said spaced perforated lines.

2. An advertising envelope, comprising sheet material in the form of an envelope having a front face divided by a perforated line extending from the top to the bottom so as to form a right hand and left hand section, miscellaneous matter or the like printed upon the left hand section and the right hand section being for the purpose of the sender's name and address, the receiver's name and address, and the necessary postage stamp, and a pair of spaced transverse perforated lines, on the bottom of the front face of the envelope at its center at the base of said vertical perforated line, and said sheet material being formed with substantially U-shaped cuts connecting the ends of said spaced perforated lines.

3. An advertising envelope, comprising sheet material in the form of an envelope having a front face divided by a line extending from the top to the bottom so as to form a right hand and left hand section, miscellaneous matter or the like printed upon the left hand section and the right hand section being for the purpose of the sender's name and address, the receiver's name and address, and the necessary postage stamp, a line of perforations being extended across the top and bottom of a portion of the envelope and connecting at the ends with U-shaped cuts, and the said dividing line on the face of the envelope being formed with perforations connecting with the top line of the perforations.

In testimony whereof I have affixed my signature.
